UNITED STATES PATENT OFFICE

149,575

DESIGN FOR A WHEEL TRIM OR SIMILAR ARTICLE

George Albert Lyon, Detroit, Mich.

Application May 6, 1947, Serial No. 138,840

Term of patent 14 years

(Cl. D14—30)

To all whom it may concern:

Be it known that I, George Albert Lyon, a citizen of the United States and a resident of the city of Detroit, in the county of Wayne and State of Michigan, have invented a new, original, and ornamental Design for a Wheel Trim or Similar Article, of which the following is a specification, reference being had to the accompanying drawing, forming a part thereof.

On the drawing:

Figure 1 is a side elevational view of a wheel trim, showing my new design;

Figure 2 is a diametric, more or less schematic sectional view of the wheel trim indicating how the same is associated with a vehicle wheel; and

Figure 3 is a fragmentary perspective view,

partly in section, of a portion of the wheel trim.

The dotted line showing in the drawing is for illustrative purposes only.

I claim:

The ornamental design for a wheel trim or similar article, substantially as shown and described.

GEORGE ALBERT LYON.
